MONSTRANCE OR THE LIKE

Ernelle Johnson, 559 Johnson St., Cocoa, Fla. 32922

Filed Aug. 26, 1965, Ser. No. 86,730

Term of patent 14 years

(Cl. D29—23)

FIG. 4.

FIG. 2.

FIG. 1.

I claim:

The ornamental design for a monstrance or the like, as shown.
